UNITED STATES PATENT OFFICE.

HENRY A. HOUSE, OF BRIDGEPORT, CONNECTICUT.

RECOIL-CHECK FOR VEHICLES.

No. 810,282.

Specification of Letters Patent.

Patented Jan. 16, 1906.

Application filed April 20, 1905. Serial No. 256,621.

To all whom it may concern:

Be it known that I, HENRY A. HOUSE, a citizen of the United States, and a resident of Bridgeport, in the county of Fairfield and State of Connecticut, have invented certain new and useful Improvements in a Recoil-Check for Vehicles, of which the following is a specification.

My invention is a recoil-check adapted to be used in connection with vehicle-springs to arrest or check a too sudden recoil after compression.

It is a well-understood fact that the breakage of springs is not due to compression, whether such compression be sudden or gradual, but the danger lies in the sudden rebound of the spring after it has been compressed.

The object of my device is to check the spring on its first attempt at recovery and then gradually allow it to resume its normal position.

To enable others to understand my invention, reference is had to the accompanying drawings, in which—

Figure 1 is a broken view of a spring, broken view of the frame or chassis of an automobile, and sectional view of the axle. This view shows the recoil-check attached to the axle with the spring and said check normal. Fig. 2 is a full-size central sectional view of the cylinder or outer casing of the recoil-check, central sectional view of separable friction-grippers in line *a a* of Fig. 4, also broken view of the strap connecting the lower end of the check with the axle. Fig. 3 is a sectional view of the recoil-check, similar to that shown at Fig. 2, except that the device is shown compressed. Fig. 4 is an upper detail plan view of the separable grippers and sectional view of four bolts projecting through said grippers.

Its construction and operation are as follows:

1 represents a cylindrical outer casing having the closed top *1^a* and the removable cap 2 at the bottom.

3 is an eye projecting from the top *1^a*, adapted to link with the lower end of the support 4, connected to the chassis 5.

6 is a strap joining the axle 7 with the lower end of the connecting-rod 8 of the recoil-check.

9 represents the upper and lower sections of an ordinary elliptic vehicle-spring located between the chassis and axle.

10 and 11 are the friction-grippers adapted to have frictional contact with the interior of the casing 1.

12 represents semicircular packings, leather or other like material, interposed between the semicircular grippers and the interior wall of the casing.

13 and 14 are interior projections of these grippers having the openings or pockets 15 and 16, in which are operatively located on the pins 17 and 18 the toggle-arm levers 19 and 20, having the curved meeting faces *b* and *c*.

21 is a block having the transverse opening 70 22 to receive the free ends of the toggle-arm levers 19 and 20. The lower end of this block has a threaded hole adapted to receive the threaded end 8^a of the connecting-rod 8.

23, 24, 25, and 26 are studs anchored in the 75 closed top or head *1^a* of the casing 1, and 27, 28, 29, and 30, Fig. 4, are holes in the top of the grippers 10 and 11, which holes freely embrace these studs.

31, 32, 33, and 34 are coiled springs 80 embracing said studs and abutting against the inside of the upper surface of the gripper-sections 10 and 11 and the nuts 35, mounted on the lower ends of the said studs.

36, Fig. 4, represents dowel-pins in the meeting faces of gripper-sections, which pins serve to prevent the vertical displacement of said sections, but do not hinder their lateral movement.

Operation: The device is adjusted to the 90 load the vehicle is supposed to carry by means of the strap 6, so that when properly set the grippers 10 and 11 will be drawn down approximately into the position shown at Figs. 1 and 2. This downward movement of the 95 grippers will compress the coiled springs 31, &c., as shown at Fig. 2. Suppose, for instance, that the vehicle has received a sudden and violent jolt. The instant the upper sections of its springs start downward the 100 stored-up tension in the coiled springs 31, &c., will loosen the grip of the sections 10 and 11 on the interior wall of the casing 1 and permit said casing to move down with the said vehicle-spring sections. If the jolt 105 has been very severe, the casing will be carried down until the grippers are in the position shown at Fig. 3, and for that matter the casing may be carried down until the interior surface of its head strikes the grippers, the 110 flexible character of the connecting-strap 6 permitting even a further downward move-

ment of the casing. The sudden jerk of the vehicle-springs on their recoil movement will tend to draw the toggle-arm levers toward a horizontal position. This outward effort of the vehicle-springs will thus result in forcing the gripper-sections firmly against the interior wall of the casing 1 and instantly check the return of the vehicle-springs. After the vehicle has passed over the obstruction which caused the sudden compression of its springs and the sudden recoil of said springs has been arrested, as before mentioned, the vehicle will have sufficiently steadied itself so that the stored-up tension in its springs will only exert an even outward strain. Under this even strain, which strain will of course be greater than the tension of the coiled springs 31, &c., the vehicle-springs and the casing will gradually recover their normal position.

To further illustrate the manner in which the recoil-check operates, let it be supposed that the casing 1 is suspended from a fixed support and a weight is attached to the rod 8 by means of a flexible connection. The grippers will be drawn down in said casing against the tension of the coiled springs a distance proportional to such weight, which weight will of course cause the toggle-arms to exert sufficient outward pressure of the gripper-sections against the interior wall of the casing to hold the weight. Now if the weight is lifted the coiled springs will force the gripper-sections back to the bottom of the casing or back a distance represented by the stored-up tension in the coiled springs. If the weight is suddenly dropped, the momentum stored up in its fall will cause the gripper-sections to be thrown outward against the interior wall of the casing the instant the downward movement of the weight is arrested, and these sections will remain firmly in contact with said casing until the momentum stored up in the falling weight has expended itself, and the instant this stage of the operation has been reached the downward pressure of the weight will be only what is represented by gravity, and, this being greater than the resistance offered by the coiled springs, the weight will gradually fall until a balance between said weight, coiled springs, and the frictional contact of the gripper-sections is established. While the operation just described is the reverse of what it would be when the device is attached to a vehicle, the principle is the same.

While I show certain means for attaching the device to a vehicle, I do not wish to be confined to any particular means, as such means can be varied to suit the circumstances of each case and the peculiar construction and arrangements of the different parts of the vehicle.

Having thus described my invention, what I claim as new, and desire to secure by Letters Patent, is—

1. A recoil-check adapted to arrest the sudden return of a vehicle-spring after compression comprising a casing expandable grippers adapted to have both a lateral and a longitudinal movement, within said casing, means for expanding said grippers under a sudden strain so as to temporarily check the recoil of the vehicle-spring, means to permit the moderate recovery of said spring, for the purpose set forth. 70

2. A recoil-check adapted to arrest the sudden return of a vehicle-spring after compression, comprising a casing, grippers adapted to have both a lateral and a longitudinal movement in said casing, means for expanding said grippers under a sudden strain so as to temporarily check the recoil of the vehicle-spring, means to permit the moderate recovery of said spring, for the purpose set forth. 75

3. A recoil-check adapted to arrest the sudden return of a vehicle-spring after compression comprising a casing, grippers adapted to frictionally engage the inner wall of said casing, toggle-arms on said grippers, a connecting-rod actuating said arms to effect said frictional engagement, recovering-springs acting against said grippers, and adapted thereby to permit of a gradual recovery of the vehicle-spring, for the purpose set forth. 90

4. The combination, in a vehicle having compressible springs, of a recoil-check adapted to arrest the sudden recoil of said springs after compression, said recoil-check connected with the vertically-movable body portion of the vehicle and the axle or other like non-vertical movable part of the vehicle, said check comprising a casing, grippers located within said casing and adapted to have both a lateral and longitudinal movement therein, toggle-arms on said grippers, a connecting-rod adapted to actuate said grippers through the medium of said grippers and against the interior wall of the casing under the compression of the vehicle-springs and thus temporarily prevent the sudden recoil of said springs, recoil-springs within the casing to relieve the outward pressure of said grippers and permit the gradual recovery of the vehicle-springs, for the purpose set forth. 105

5. The combination, with a vehicle having compressible springs, of a recoil-check connected with the vertically-movable body portion of the vehicle and the axle or other like non-vertical movable part of the vehicle, one of said connections being flexible, said recoil-check comprising a casing, grippers within said casing and adapted to have both a lateral and a longitudinal movement therein 120 and always in frictional contact with the interior wall of the casing, toggle-arms pivotally supported on said grippers, a connecting-rod adapted to actuate said grippers against the interior wall of the casing under the com- 125 130

pression of the vehicle-springs and thus temporarily check the sudden recoil of said springs, means to partially release the frictional contact of said grippers and permit the gradual recovery of the vehicle-springs, for the purpose set forth.

6. The combination, in a vehicle having compressible springs, of a recoil-check comprising a casing, a connecting-rod longitudinally movable therein, means for connecting the casing and connecting-rod to the vehicle, one to a vertically - movable part, and the other to a non-vertical movable part, grippers adapted to have both a lateral and longitudinal movement in the casing, toggle-arms having one of their ends pivotally supported to said grippers, their free ends operatively connected to said connecting-rod so that, when the vehicle - springs are compressed, said grippers are expanded forcibly against the casing to temporarily check the recoil of said springs, means for partially releasing the contact of said grippers to permit of their gradual recovery, for the purpose set forth.

7. The herein-described recoil-check com-

prising a casing, expandible grippers therein, toggle-arms having one of their ends pivotally supported on said grippers, a connecting-rod, the free ends of the grippers connected with said rods, studs secured to said casing and passing freely through said grippers, springs embracing said studs having a kicking-post both on the studs and grippers, for the purpose set forth.

8. The herein-described recoil-check comprising a dust-proof casing, expandible grippers therein, toggle-arms having one of their ends pivotally supported on said grippers, a connecting-rod, the free ends of the grippers connected with said rods, studs secured to said casing and passing freely through said grippers, springs embracing said studs having a kicking-post both on the studs and grippers, for the purpose set forth.

Signed at Bridgeport, in the county of Fairfield and State of Connecticut, this 15th day of April, A. D. 1905.

HENRY A. HOUSE.
